(57) CLAIM

The ornamental design for a garment box insert, as shown and described.

DESCRIPTION

FIG. 1 is a perspective view of a garment box insert according to a first embodiment of the present design;

FIG. 2 is a front view of the garment box insert shown in FIG. 1;

FIG. 3 is a side view of the garment box insert shown in FIG. 1, the opposite side view being a mirror image thereof;

FIG. 4 is a rear view of the garment box insert shown in FIG. 1;

FIG. 5 is a top view of the garment box insert shown in FIG. 1;

FIG. 6 is a bottom view of the garment box insert shown in FIG. 1; and,

FIG. 7 is a perspective view of a garment box insert according to a second embodiment of the present design.

The broken lines shown in the drawing disclosure are for illustrative purposes only and form no part of the claimed design.
